PIPE

Charles P. Nash, Jr., Charlottesville, Va.

Application May 5, 1938, Serial No. 206,258

1 Claim. (Cl. 131—198)

This invention relates to tobacco pipes.

The chief object of the invention is to provide a novel pipe in which the temperature of the smoke is fully under control of the smoker, and in which the pipe, by a novel arrangement for the admission of auxiliary air is kept dry.

The objects are accomplished by providing a main bowl for the reception of the tobacco to be burned during the smoking, and an auxiliary bowl for the reception of a second quantity of tobacco that acts as a filter and regulator for the passage of auxiliary air that is mixed with the smoke after the latter has left the main bowl and before it reaches the mouth of the smoker.

15 In the drawing:

Figure 1 is an elevation of a pipe embodying the invention;

Figure 2 is a plan view; and

Figure 3 is a vertical section.

20 Describing the drawing more particularly, the pipe comprises a stem 6, having a mouthpiece 7, and a passage 8. Carried by the forward end of the stem is a bowl designated generally 9, and preferably formed from a single block of material, such as briar. The bowl 9 has a main chamber 10 for the reception of the tobacco to be smoked, and which may be formed in any suitable manner as to size and shape.

25 Adjacent the main bowl 10 and preferably located just to the rearward thereof, is an auxiliary bowl 11 that is preferably smaller in cross sectional area and also less in height than the main bowl 10. The size of the bowl 11 is small in order to avoid a waste of tobacco, as will be more fully described later.

30 The bowl 11 is for the purpose of receiving an auxiliary body of tobacco 12 that acts as a filter and regulating means for the passage of air. The bowl 11 is of sufficient size to permit the introduction of a finger of the user in order to tamp the tobacco and thereby regulate its compression and the amount of air that may pass through it.

35 The bowl 11 has at its bottom an outlet 13 in the usual fashion of tobacco pipes. The bowl 11 has an outlet 14 that merges with the outlet 13 of the main bowl at a point 15 outside of the tobacco receiving chambers of both bowls. The merged outlets 13 and 14 communicate with a passage 16, that in turn communicates with the 40 passage 8 of the stem.

45 The use of the above described pipe is as follows:

Both of the bowls 10 and 11 are filled with tobacco and that in the main bowl 10 is ignited.

50 It will be appreciated that air will be drawn

through both of the outlets 13 and 14 through the stem of the pipe, and that consequently a mixture of smoke from the bowl 10 and air from the bowl 11 will pass through the stem to the mouthpiece 7.

The proportions of air and smoke that reach the mouth of the smoker control the temperature, and these proportions may be accurately controlled by the smoker, by adjusting the compression of the tobacco in bowl 11, through which the air passes, whereby the amount of air that is mixed with the smoke is controlled.

The admission of air to the stream of smoke after the latter has left the outlet 13 of the main bowl 10 prevents the condensation of moisture upon the walls of the stem, whereby the pipe is maintained in a clean and dry condition.

Obviously, materials other than tobacco may be used in the bowl 11. In order to maintain the advantage of adjustability of the temperature 20 of the smoke to suit the smoker, the material used should be compressible so that the passage of air through the bowl 11 may be controlled by pressing it down and, thereby, packing it. Tobacco forms a convenient and readily accessible 25 material and, therefore, is regarded as preferable.

It has been determined that in the process of smoking when the auxiliary bowl is packed to substantially the same degree of compression as 30 the main bowl, the air and smoke will be mixed in substantially equal proportions, and a cool and comfortable smoke will be presented to the mouth of the smoker.

Due to the small size of the bowl, the amount 35 of tobacco used as the air controlling medium is negligible and, as a matter of fact, it may be mixed with tobacco for use in the bowl 10 after it has become dried through heat from the burning tobacco in the main bowl and the passage of air through it.

In order to confine the charge of filtering material 12 within the bowl 11 a cover member 17 may be applied to the bowl. Conveniently such cover will be hinged as at 18 and will be provided 45 with a spring holding device as at 19. Such a cover is of value in that it protects the filtering material from being disturbed and also prevents the escape of the material to the smoker's 50 pocket when the pipe is so carried.

While I have in the above description disclosed what I believe to be the preferred and practical embodiment of the inventive concept, it will be understood to those skilled in the art that the specific details are merely illustrative 55

of other equivalent constructions which may be developed in the course of use, and that the invention is to be determined not by the details as shown and described but by a fair interpretation 5 of the appended claim.

What I claim is:

Tobacco pipe comprising in combination, a pair of bowls, and a stem having a smoke passage, said bowls being connected in multiple to said 10 smoke passage whereby the draft from either bowl does not pass through the other bowl, said bowls being adapted to serve respectively as a combustion chamber for tobacco and as an auxiliary air chamber admitting cooling air to the

smoke passage, the bowl which constitutes the auxiliary air chamber being large enough to admit the finger, and having the bottom thereof above said smoke passage whereby it is above the moisture level of the condensate formed in said 5 pipe, a mass of tobacco in the last mentioned bowl adapted to be compressed by the finger of the user to adjustably regulate its penetrability to air, whereby the draft condition in the combustion chamber as well as the proportion of cool air 10 admitted to the smoke, may be controlled, said bowls having a common wall serving as a medium for heat exchange.
